(57) CLAIM

The ornamental design for, motorcycle or motorcycle replica, as shown and described.

DESCRIPTION

FIG. 1 is a first perspective view of motorcycle or motorcycle replica, showing our new design;

FIG. 2 is a second perspective view thereof;

FIG. 3 is a front elevation view thereof;

FIG. 4 is a rear elevation view thereof;

FIG. 5 is a top plan view thereof;

FIG. 6 is a right side elevation view thereof; and,

FIG. 7 is a left side elevation view thereof.

The lighter half-tone portions shown illustrate environmental structure for the motorcycle or motorcycle replica that forms no part of the claimed design.
